RECORD BEGINNING GUIDE FOR SOUND REPRODUCING MACHINES

Filed Jan. 10, 1921

2 Sheets-Sheet 2

UNITED STATES PATENT OFFICE.

THOMAS H. LOY, OF BELLAIRE, OHIO.

RECORD-BEGINNING GUIDE FOR SOUND-REPRODUCING MACHINES.

Application filed January 10, 1921. Serial No. 436,145.

To all whom it may concern:

Be it known that I, THOMAS H. LOY, a citizen of the United States, residing at Bellaire, in the county of Belmont and State of Ohio, have invented certain new and useful Improvements in Record-Beginning Guides for Sound-Reproducing Machines, of which the following is a specification.

The present invention has for its object 10 to provide means for facilitating the positioning of the reproducer of a sound reproducing machine with respect to a record on the record support so that the stylus will contact at a predetermined point of said record 15 according to adjustment of said means.

More specifically stated, the invention consists of a device constituting a stop or guide enabling the operator in playing of sound records to accurately deposit the 20 stylus of the sound box at the precise point for cooperation with the sound groove of the record or with the initial sound producing portion of the same.

At the present time sound reproducing machines of well-known types lack any means by which the operator may bring the reproducer into proper playing position without first testing for the place where the musical reproduction is started. The result is that 25 the reproducer is dropped upon the record long before the sound groove is reached under the actuation of the feed mechanism for shifting the reproducer, or in those machines which rely upon the record groove to 30 shift the reproducer, it becomes necessary to continue to try for deposit of the stylus in the groove itself. Owing, however, to the 35 minuteness of the groove and the difficulty of discerning it because of the lack of contrast upon the black surface, the necessity for "testing" even when the groove is found to bring the stylus to the point where the 40 reproduction of the music commences, involves a process which makes very unsatisfactory the playing of sound reproducing 45 records.

On the other hand, with my device applied to the instrument, the operator is able to precisely deposit the reproducer or its stylus 50 at the point desired, and this may be accomplished even in the dark or where the operator does not possess the powers of sight.

An important feature of my invention re-

sides in the construction of the device as an 55 attachment which is capable of being cheaply manufactured and readily applied to those sound reproducing machines not originally equipped with means of this character, the attachment being preferably 60 formed so as to eliminate any necessity for use of special tools to carry out its application.

A further object in view is to provide an 65 attachment of this nature whereby adjustment in a most simple manner adapts it for functioning with different sizes of records.

These and such other objects as may hereinafter appear are attained by the novel construction, combination and arrangement of 70 parts to be hereinafter specifically described and claimed. Reference will now be had to the accompanying drawings forming a part of this specification, wherein:

Figure 1 is a top plan view of a sound re- 75 producing machine having my invention applied thereto.

Figure 2 is a view in elevation showing 80 more clearly the cooperation of the feed mechanism part with the stop means of this invention, the parts of the sound reproducing machine being shown in section.

Figure 3 is an enlarged top plan view of 85 the invention alone.

Figure 4 is a view in elevation looking at 90 the end upon which the stop pin is mounted.

Figure 5 is a view in elevation of the opposite end, showing more clearly the formation of the means for retaining the indicator. 95

Figure 6 is a sectional view on a line 6—6 of Figure 3.

Throughout the following detailed description, and on the several figures of the drawings, similar parts are referred to by 95 like reference characters.

The subject matter of this invention is designed to be applied to different types of sound reproducing machines, and the type illustrated in the drawings is employed 100 merely to exemplify the manner in which it may be carried out as regards those sound reproducing machines which employ positive feed mechanism for shifting the sound reproducer in playing over the face of the 105 record.

These machines referred to have a feed rack A beneath the supporting plate or base

B, which feed rack is mounted upon the reproducer supporting shaft A' provided with the handle A''. In the playing of a record the reproducer is shifted toward the 5 periphery of the record upon the turn-table and then is lowered into position bringing the stylus in contact with the record, such lowering action involving a lowering movement of the feed rack A referred to which is 10 engaged thereby with a rotary part that causes the movement of the reproducer in the playing operation. This mechanism is clearly disclosed in my co-pending application filed December 28, 1920, Serial No. 15 433,709 for the improvements in controlling mechanisms for sound reproducing machines.

In the specific embodiment of my invention illustrated, the construction is designed 20 to constitute an attachment readily applicable to sound reproducing machines of the known type or types referred to and it comprises the two clamping parts 1, 2, the former having a depending flange 3 and 25 the latter a corresponding flange 4 which are engageable with the base plate B to hold the device in position upon said base plate at the point desired. The two clamping members are firmly connected together by 30 the clamping screw 5 which fixes the clamping parts and holds them in rigid clamped position. Upon the part 1 is pivotally mounted an indicator member 6 and superposed with respect to this part is an adjustable stop carrying plate 7 pivotally secured at 8 which is also the pivot for the indicator part 6. The adjustable member 7 is slotted at 9 to receive an adjusting screw 10 which passes therethrough and connects with the 40 extension 6' of the indicator part. The parts 6 and 7 are provided with flanges 7^a and 6^a, respectively, and connected by means of a retaining screw 11, a spring 12 being interposed between the flanges. At one side 45 the part 7 is apertured to receive a vertically positioned stop pin 13 freely mounted for vertical movement and depending through the base B into a position for co-action with the feed rack A hereinbefore 50 described. The clamping plate 2 is so stamped or constructed as to embody a lateral extension 14. In the illustration of the present case the metal is bent upwardly and then downwardly into a horizontal position, 55 the extremity being re-bent as at 14' so as to supportingly engage with the surface of the base B. This extension 14 is slightly curving and the outer edge of the same is bent downwardly to provide spaced flanges 60 14^a forming a series of stop notches 14^b. Upon the surface of this extension suitable indicia is positioned with respect to the notches to indicate different sizes of records so that the operator is able to adjust the 65 indicator part 6 to the proper position at will.

The end of the indicator engages in the notches and fixes the position of the stop pin 13 in an obvious manner.

The adjustment of the part 7 which carries the part 13 with respect to the indicator member 6 is to obtain the fine adjustment of said pin which will insure the co-action of the stylus with the beginning of the sound groove of records of a predetermined diameter, and this adjustment may be made 70 at the factory so as to require no further attention on the part of the operator, or the operator may readily accomplish its adjustment by loosening the screw 10 slightly and rotating the adjusting screw 11 in the proper direction to shift the pin inwardly and outwardly, so to speak. If the size of the record changes, it is only necessary, to modify the position of the pin 13 accordingly, to adjust the indicator 6 so that it will engage in 75 the proper notch representing the co-action for the particular size of record involved.

In the operation of this machine, the adjustment of the parts having been made, the operator in playing a record, moves the reproducer freely from its outermost position toward playing position until such movement is stopped by contact of the feed rack with the side of the pin 13 lying in its path of arcuate movement. The operator is at 80 once advised that the reproducer is in the proper position over the beginning of the sound groove and he thereupon lowers the reproducer in the well-known manner until the stylus engages in the groove, the lowering movement being best carried out by holding the rack against the side of the pin which guides the said lowering movement into a position where the rack escapes the 85 end of the pin. At this point the stylus is in the precise position desired for commencement of the playing and the playing operation takes place in the customary manner. Since the rack is freed of the pin the playing 90 operation is permitted and when the reproduction is terminated the operator, if the machine is not an automatic repeating machine, manually raises the reproducer and in so doing the rack A raises the stop pin 13, the latter sliding upon the upper surface of the rack during the reverse movement of the reproducer until the latter has been shifted to such position that the pin will escape the edge of the rack and drop into position for 95 impeding its movement in the opposite direction as when starting the record anew, or playing another.

It will be perfectly obvious from the foregoing that once the adjustment has been made for the stop means, no attention is required on the part of the operator to precisely deposit the reproducer in the proper position for playing purposes.

Obviously the device may not be made as 100 an attachment as it is within the purview of 105

this invention to carry out the object by embodying its elements in the machine when originally manufactured so that the same result of stopping and guiding the beginning 5 of a record may be accomplished.

In those machines of this type which are provided with repeat mechanisms, the reproducer return is under the control of the latter, so that it is not moved in its return 10 to record beginning position far enough to permit the pin 13 to escape the edge of the rack so that said pin freely slides upon the upper surface of the rack during all of the repeat operations and until the reproducer is moved beyond the initial sound groove, 15 speaking with reference to the direction of movement away from the center of the record.

Having thus described my invention, what 20 I claim as new and desire to secure by Letters Patent is—

1. In a sound reproducing machine, including a record support, the combination with reproducer mechanism, of stop means 25 for controlling the initial coaction of the reproducer with the record, said means being constructed and arranged to stop movement of the reproducer at record beginning position preliminary to playing, said reproducer 30 mechanism thereafter coacting with the stop means, to maintain the same in inoperative relation.

2. In a sound reproducing machine, including a record support, the combination 35 with a reproducer, of stop means for controlling the initial coaction of the reproducer with the record, said means having a part disposed to stop movement of the reproducer in a direction toward the axis of the record 40 support from positions beyond record beginning position, and means for rendering the stop means inoperative while the reproducer is within the zone of record playing.

3. In a sound reproducing machine, including a record support, the combination with reproducer mechanism, of stop means 45 for controlling the initial coaction of the reproducer with the record, said stop means having a part disposed in the path of movement of the reproducer, means stopping free movement of the reproducer from points beyond the zone of the record sound groove toward initial playing position, said means being held in inoperative position after deposition 50 of the reproducer in playing position on the record groove and during non-playing movements of the reproducer until the reproducer is moved beyond the said zone.

60 4. In a sound reproducing machine, including a record support, a reproducer and means for effecting movement of the reproducer in playing operation, of stop means including an abutment member normally 65 positioned to be impinged by the means for

moving the reproducer aforesaid when the reproducer is moved from points beyond the record beginning position and elevated with respect to the record support, said stop means being cleared when the reproducer is 70 in contact with the record, said abutment member being movably mounted to be displaced and held in inoperative position in movements of the reproducer within the zone of the sound record. 75

5. In a sound reproducing machine, including a record support, a reproducer and means for effecting movement of the reproducer in playing operation, of stop means including an abutment member normally 80 positioned to be impinged by the means for moving the reproducer aforesaid when the reproducer is moved from points beyond the record beginning position and elevated with respect to the record support, said stop means being cleared when the reproducer is 85 in contact with the record, said abutment member being movably mounted to be displaced and held in inoperative position in movements of the reproducer within the zone of the sound record by the means aforesaid for moving the reproducer. 90

6. In a sound reproducing machine, the combination with a record support, a reproducer and feed member for causing playing movement of the reproducer, of stop means for controlling the positioning of the reproducer at record beginning position including a part gravitatively assuming a position to be impinged by the feed member 95 upon movement of the reproducer toward record beginning position from points beyond the same, said feed member coacting with said gravitational part to hold the same in inoperative position during other movements of the reproducer than those aforesaid. 100

7. In a sound reproducing machine including a record support, a reproducer and feeding mechanism for causing travel of said reproducer during playing operation, of stop means adjustable to co-act with a part of the feed mechanism aforesaid upon free movement of the reproducer toward the axis of said record support, and means for actuating the reproducer to effect deposition of the same upon a record, said stop means being rendered inoperative to impede movement of the reproducer incident to the depositing action aforesaid. 110 115

8. In a sound reproducing machine the combination with a record support and a reproducer, of a single stop device detachably connected to said machine in position to co-act with a part of the reproducer, said stop device including an adjustable section for predetermining the point in the movement of the reproducer toward the periphery of the sound record corresponding to the desired point of co-action of the reproducer 120 125 130

with the record, and separate adjusting means cooperating with said adjustable section for adjusting the stop device to accord with variations in the diameter of the sound record.

9. In a sound reproducing machine the combination with a record support and reproducer, of a single stop device for limiting movement of the reproduced toward the record support, including means for attaching the device in operative position, means for adjustment in stop position to accord with variations in the point of commencement of the sound groove of the record and separate means for adjustment of said device to accord with sound records of varying diameters.

10. As a new article of manufacture a record beginning stop device for sound reproducing machines constituting an attachment applicable to said machines in position for co-action with a rotary part thereof, and comprising a gravitational adjustable member against which said rotary part is adapted to impinge.

11. As a new article of manufacture a record beginning stop device for sound reproducing machines constituting an attachment applicable to said machines in position for coaction with a rotary part thereof disposed to control the feed of a reproducer, and comprising securing means, an adjustable member against which said rotary part is adapted to impinge, and means for adjusting said member to control the co-action of the rotary part with the same sooner or later with respect to a certain record.

12. A record beginning stop and guide for sound reproducing machines comprising an attachment, including means for con-

necting the device upon the sound reproducing machine, a single abutment member, means for adjusting said abutment member, and separate means carried by the first mentioned adjusting means for adjusting said abutment member in degrees relatively smaller than by the first adjustment means.

13. As a new article of manufacture, a stop device attachment for sound reproducing machines comprising clamping sections for connecting said device to said machine, a separate section mounted upon one of said clamping sections and movable relative thereto, and a freely gravitating stop member carried by said separate section.

14. As a new article of manufacture, a stop device attachment for sound reproducing machines comprising clamping sections for connecting said device to said machine, a separate section mounted upon one of said clamping sections and movable relative thereto, a freely gravitating stop member carried by said separate section, and an adjustable section for shifting said separate section and stop member.

15. As a new article of manufacture, a stop device attachment for sound reproducing machines comprising clamping sections for connecting said device to said machine, a pivoted section mounted upon and movable relative to one of the clamping sections, a stop member carried by said pivoted section and depending therefrom, means for adjusting said pivoted section to vary the position of the stop member, and an adjustable section upon which said pivoted section and stop member are mounted for bodily movement to shift said parts relatively to the clamping sections.

In testimony whereof I affix my signature.
THOMAS H. LOY.
